UNITED STATES PATENT OFFICE.

JOHN W. BROOKS, OF STAMFORD, CONNECTICUT.

VALVE-SEAT-REFACING TOOL.

1,127,175.

Specification of Letters Patent.

Patented Feb. 2, 1915.

Application filed May 19, 1914. Serial No. 839,573.

To all whom it may concern:

Be it known that I, JOHN W. BROOKS, a citizen of the United States, residing at Stamford, in the county of Fairfield and State of Connecticut, have invented certain new and useful Improvements in Valve-Seat-Refacing Tools, of which the following is a specification.

This invention comprehends certain new and useful improvements in valve seat refacing tools and has for its primary object to provide a device of this character which will be of extremely simple construction and operation and composed of the minimum number of parts.

Another object is to provide a device of this character in which the stem will be composed of two sections with the blade carrying head secured between said sections and serving to connect the same.

A further object of this invention is to provide an improved form of head with blades removably secured in the same.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which—

Figure 1 is an elevation of the complete device, Fig. 2 is a detail longitudinal section on the line 2—2 of Fig. 1, Fig. 3 is a bottom plan view of the head removed, Fig. 4 is a top plan view of the intermediate section of the head, with the blades removed, Fig. 5 is a detail transverse section on the line 5—5 of Fig. 1, and Fig. 6 is a detail perspective view of one of the blades.

Referring in detail to the drawings by numerals, 1 designates the lower section of the stem which serves to guide the tool during operation of the same, as will be clearly understood, and which is provided with a reduced threaded upper extremity 2 to receive the lower section 3 and intermediate or main section 4 of the head of the tool, it being understood that the lower section 3 of the head is provided with a central opening to receive the reduced threaded extension 2 and is secured to the bottom of the blade carrying head section 4, by screws or

other suitable securing members 5. It will also be understood that the blade carrying section 4 is provided with a threaded longitudinal bore 6, in order that the threaded reduced extension 2 may be securely fastened in the section 4.

The section 3 is in the form of a disk and serves to close the lower end of the longitudinal radially directed slot 7 formed in the edge of the section 4 to receive the removable valve engaging blades 8 which are provided with beveled or inclined working edges 9 for engagement with a valve seat for the purpose of grinding or refacing the same. The blades 8 are retained in position within the slots 7 by means of set screws 10 extending transversely through the head section 4 and having their ends engaged in sockets 11 formed in one side of the blades 8, suitable recesses 12 being formed in the sides of said section 4 to accommodate a screw driver or other tool employed for turning the set screws 10. A reduced lower threaded extremity 13 of the upper stem section 14 is also threaded in the longitudinal bore 6 of the main portion intermediate the head section 4 and inward movement of said threaded extremity 13 is prevented by the stop shoulder 15 formed in the inner end of said threaded extremity and adapted for engagement against the upper face of said section 4. The upper extremity 14 is also provided with an enlarged threaded portion 16 adjacent its lower end and around which is threaded the upper head section 17 which serves as a jam nut for engagement against the upper face of the main or intermediate head section 4 and thereby prevent independent rotation of said section 4 and the upper stem section 14.

The upper head section 17 or jam nut also serves to bear against the upper end of the removable blades 8 and thereby coöperate with the lower head section which bears against the lower ends of said blades 8, to securely clamp said blades and prevent movement of the same in the head member 4.

The upper portion 18 of the upper stem section 14 is preferably of rectangular form in order that the device may be readily secured in a brace, if desired. The upper portion 18 is also provided with a transverse opening through which is engaged a handle 19 which may be employed for rotating the device and said handle 19 is secured in ad-

justed position by means of a set screw 20 in the upper end of said upper stem section 14 and adapted to bear against said handle 19 and thereby prevent movement of the 5 same through the upper stem section 14. It will be seen that the handle 19 may be readily inserted in the opening provided for the same or removed therefrom and when in position will serve as means by 10 which the device may be rotated to move the blades 8 upon the valve seat and thereby smooth and reface the latter.

From the foregoing, it will be readily seen that this device, owing to the extremely simple construction of the various parts, may be readily and cheaply manufactured and will be strong and durable as well as highly efficient in use.

What is claimed is:—

20 1. A device of the class described comprising a stem, a guide, said stem and guide having adjacent reduced portions, a head mounted upon said reduced portions and serving to connect said stem and guide, 25 said head being provided with blade accommodating slots, securing means engaged through said head, blades removably positioned in said slots, said securing means be-

ing engaged with said blades, and means engaged against opposite faces of said head 30 and against the blades to secure the head against movement and prevent movement of the blades in said slots.

2. A device of the class described comprising a stem, a head mounted upon said stem and provided with radially directed slots extending from the upper face to the lower face of said head, a guide projecting from said head and in alinement with said stem, blades secured in said slots, means for preventing withdrawal of said blades, means mounted upon said stem and engaged with the head and blades to prevent movement of the same upon said stem, means secured to the head and adapted for co-operation with the last mentioned means to prevent movement of the blades, the second mentioned means being mounted upon the guides, and means for rotating the stem.

In testimony whereof I affix my signature 50 in presence of two witnesses:

JOHN W. BROOKS.

Witnesses:

BENJAMIN H. MEAD,
FLOYD B. BARTRAM.
